UNITED STATES PATENT OFFICE.

DUDLEY R. DALE, OF TOLEDO, OHIO, ASSIGNOR TO THE S. M. JONES COMPANY, OF TOLEDO, OHIO, A CORPORATION OF OHIO.

SUCKER ROD.

Application filed May 28, 1923. Serial No. 641,862.

To all whom it may concern:

Be it known that I, DUDLEY R. DALE, a citizen of the United States, and a resident of Toledo, in the county of Lucas and State of Ohio, have made an Invention Appertaining to a Sucker Rod, which invention is fully set forth in the following specification.

My invention has for its object to provide a means for protecting relatively reciprocating metal parts from wear caused by the reciprocatory movements. The invention is of special advantage when embodied in a construction wherein there is considerable loose lateral play between the reciprocating parts. The invention particularly has for its object to provide a means for protecting the metal tubing of oil wells from the wearing action of the reciprocating sucker rod. The sucker rods are formed of joined sections having connecting parts of larger diameter than the body of the sucker rod for joining the sections of the sucker rod together. In oil wells of considerable depth the variation of the strata through which the well extends causes considerable deviation from the vertical, with the result that when the sucker rod is placed in position and reciprocated to pump the oil from the well the parts of the sucker rod are pressed with considerable pressure against the tubing that forms the wall of the well. Continual reciprocation of the sucker rod causes wear and in a very short time causes leakage and loss. A variety of protective devices have been suggested in the art, but I have found that by forming the connecting parts of a softer metal than that of which the tubing is formed, the wear and tear is quite completely eliminated. The metal of the connectors being different from that of which the tubing is formed, the friction between the parts is greatly reduced. The connecting parts, moreover, are considerably larger than the body of the sucker rod so that the bearing points as between the reciprocating sucker rod and the tubing will be on the connectors, notwithstanding the deformation of the oil well produced in the drilling of the well.

Furthermore, as the connectors wear they may be readily renewed or replaced and thus save the expense of new forgings forming the ends of the sections of the sucker rods. Also connectors of different sizes may be used for connecting sucker rods of the same

size. The forged ends of sucker rods have as a rule a certain relative size to the diameter of the tubing. By my invention, the same sized rod may be used with connectors of varying sizes and thus may be used in 60 tubing of different diameters. The size of the connector used will be such as to maintain the proper relation between the size of the connector to the diameter of the tubing.

An embodiment of the invention is illustrated in the accompanying drawings wherein is shown an oil well sucker rod that is described in detail hereinafter.

Referring to the drawings, Fig. 1 illustrates a side view of one form of connector 70 located at the joints of the sections of the sucker rod. Fig. 2 illustrates a broken view of one of the sections. Fig. 3 illustrates a modified form of connector. Fig. 4 illustrates a broken view of the sucker rod having the connecting means shown in Fig. 3. Fig. 5 illustrates a side view of the connector shown in section in Fig. 3.

In Figs. 1 and 2, 1 indicates sections of a sucker rod. The ends of the sucker rod have 80 threaded portions 4 which are known as pins. A relatively long sleeve is secured to the lower end of each section of a sucker rod. Enlarged portions or shoulders 5 are located at the bases of the threaded pins 4. 85 The sleeves 2 are provided with thin or feathered edges 6. The sleeves 2 are threaded onto the lower ends 4 until the edge portions 6 extend over the shoulders 5 and the sleeves abut against the shoulders 5. The 90 thin edges 6 of the sleeves 2 are then bent or crimped down over the shoulders 5 so as to make secure the sleeves 2 to the lower end of the sucker rod. The ends of the sucker rod are also provided with flattened portions 7 95 whereby a wrench grip may be obtained in forming up the sucker rod by connecting the sections together. When, therefore, the edges 6 are bent over the shoulders 5, they engage the ends of flat portions 7 of the 100 lower ends of the sucker rods and rotation or loose play as between the sleeves 2 and the lower ends of the sucker rod is prevented notwithstanding the continual reciprocatory movement of the sucker rod in the 105 operation of the pump. If desired, the flanges 6, after they have been bent down over the shoulders 5, may be spot-welded and thus further secured.

The upper end of each section of the 110

sucker rod is provided with a relatively short sleeve or collar 8 through which the upper pin 4 of each joint of the sucker rod protrudes. The sleeve 8 is also provided 5 with a thin edge portion 6 of a form like unto that of the sleeve 2, while the upper end of each section of the sucker rod is also provided with a shoulder 5 over which the thin edge portion 6 of the sleeve 8 is bent 10 and secured in the same manner that the thin edge portion of the sleeve 2 is secured to the sucker rod.

The sections of the sucker rod are joined together by tightly screwing the sleeve 2 15 of each consecutive section of the sucker rod onto the pin 4 of each preceding section of the sucker rod as the sections thus united are lowered into the tubing of the well. The sleeves 2 and the collars 8 have the same 20 diameter, and moreover, the ends slope toward the axis of the sucker rod. Consequently a smooth cylindrical surface having a diameter considerably larger than any of the other parts of the sucker rods is presented 25 to the surface of the tubing, with the result that bearing or rubbing points of the sucker rod and the vibration and pounding that is caused by the reciprocatory movements of the sucker rods is sustained on the 30 sleeves that surround the ends of the sections of the sucker rod. The sleeves 2 and 8 form soft steel boxes that take the wear and thus prevent the wear of the reciprocatory and vibratory movements on the tubing. 35 The boxes are formed of low carbon steel and form bearing and guiding surfaces in the movement of the sucker rod along the tubing, while the sections of the rod and the tubing are formed of high carbon steel.

40 In the form of construction illustrated in Fig. 3, which is known as the double pin type sucker rod, the sleeves 8 are secured to both ends of the sucker rods and threaded onto the pins 4 and having their flanges 6 bent over the shoulders 5. A sleeve coupler 45 9 is threaded onto the lower pin of each section of the sucker rod until it abuts with

the sleeve 8 located on that end of the sucker rod. The connector 9 is threaded onto the upper pin 4 of the uppermost section of the 50 sucker rod in the top of the well as the sucker rod is being formed and lowered, section by section, until it abuts the sleeve 8 located on the upper end of that section. The connector 9 is provided with flattened 55 portions located on opposite sides, as at 10, whereby a wrench grip may be readily obtained and a secure coupling as between the sections of the sucker rod may be produced. This form or type of sucker rod will also 60 protect the casing since the sleeves 8 and the couplings 9 located at the joints of the sections have a diameter larger than any other part of the sucker rod and are formed of soft low carbon steel, and consequently of a 65 metal different from that of which the tubing is formed.

I claim:

1. In an oil well jointed sucker rod, each 70 section of the sucker rod having threaded pins, and enlarged portions forming shoulders, sleeves surrounding the base of the pins and having feathered edges crimped down over the shoulders to prevent rotation of the sleeves relative to the pins, means for connecting the sections together, the said sleeves having a diameter greater than the other parts of the sucker rod and forming bearing 75 parts for the sucker rod.

2. In an oil well jointed sucker rod, each 80 section of the sucker rod having threaded pins, and enlarged portions forming shoulders, sleeves surrounding the base of the pins and having feathered edges crimped down over the shoulders and spot-welded 85 thereto to prevent rotation of the sleeves relative to the pins, means for connecting the sections together, the said sleeves having a diameter greater than the other parts of the sucker rod and forming bearing parts for 90 the sucker rod.

In testimony whereof, I have hereunto signed my name to this specification.

DUDLEY R. DALE.
